SILENCING AND ANTISIPHONING MEANS FOR WATER CLOSETS

Filed Jan. 27, 1936

UNITED STATES PATENT OFFICE

2,086,637

SILENCING AND ANTISIPHONING MEANS
FOR WATER CLOSETSEmil Price and William A. Pfister, Los Angeles,
Calif.

Application January 27, 1936, Serial No. 60,972

2 Claims. (Cl. 137—69)

This invention relates to combined silencing and anti-siphoning means for water closets or other water or liquid containers adapted to be supplied with water or liquid from a source of supply under pressure such as the customary water supply system commonly employed in connection with such tanks, and an object of the invention is to provide simple and highly effective means whereby water can be conducted to the tank in an almost silent manner and for automatically opening the "hush" or filling tube of the tank to the atmosphere as soon as the water in the tank has reached the intended level.

15 Among other important features of the invention, the following are illustrative of those upon which particular stress is laid:

To provide means broadly wh'ch will function as above set forth and which will include a highly novel arrangement of parts enabling convenient adaptation of the invention to the customary ball cock without requiring any great alteration in the construction thereof;

20 To provide anti-siphoning means for automatically establishing communication between the filling tube and the atmosphere, hence between the source of supply and the tank as soon as the tank is filled and for automatically preventing such communication during the interval that the tank is being filled, the arrangement being such that the pressure of the water in its movement to the tank will render automatic the action of the mechanism employed;

25 To provide a valved automatic vent for the filling tube which can be wholly incorporated in the filling tube;

30 To provide a valved automatic vent, the effective elevation of which is always above the intake port of the ball cock to thus insure proper venting of the supply line in time with the filling operation;

35 To provide an anti-siphoning means and silencer which, when embodied in the filling tube, will not add materially to the manufacturing cost of the tube;

40 To provide an anti-siphoning and silencing means which will be positive of operation under all customary conditions and fool-proof and not apt to be readily placed out of order;

45 To provide a valve in the filling tube, the form of which will serve in the regular operation thereof to prevent formation of incrustation of the walls of the bore of the chamber in which the valve works, thus eliminating a probable cause for rendering the valve inactive at

critical periods in the operation of the mechanism.

With the above and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit of the invention.

In the drawing,

Figure 1 is a view partly in irregular vertical section and partly in elevation showing the invention applied;

Figure 2 is a vertical section through the filling tube and a portion of the ball cock;

Figure 3 is a view somewhat like Figure 1 showing the position of the filling tube valve to close the atmospheric vent of said tube as when water is flowing to the tank from a source of water supply under pressure;

Figure 4 is a horizontal section taken on line 4—4 of Figure 1;

Figure 5 is a section on line 5—5 of Figure 1;

Figure 6 is a perspective view of the valve element of the filling tube valve.

In carrying the invention into practice, T represents a water-closet supply tank; P the vertical pipe adapted to be connected as customary, with a source of water under pressure; B the ball cock at the upper end of pipe P, the same having a valve seat S and a co-operable vertically movable ball-controlled plug P1 connected by the usual linkages L to the float rod R. When the rod R is fully raised, the plug P1 closes the intake orifice O in the seat S and admission of water to the ball cock ceases. When, however, the rod lowers, the plug is raised and water will pass to the outlet O1 of said ball cock. All of these features just above described are old and well known in the art and are merely referred to herein as a means of disclosing the intended relationship thereof to each other and to the features embodying our invention, as will unmistakeably enable any person trained in the art to practice the invention.

The outlet O1 includes a short lateral nipple or boss 10 into which is threadedly fitted one end of a short tubular extension 11 of a vertical valve casing 12, the upper end of which is located above the outlet O1. The lower end of said casing has the upper end of a filling tube 12 fitted thereto to pass water to tank T. The tubular extension 11

traverses the bore of the casing 12 as shown in Figures 1, 2 and 3 of the drawing and is formed with an upwardly directed outlet orifice 13, disposed axially of the casing bore and thereby 5 adapted to direct a jet of water upwardly into the cupped underside of a vertically movable valve element 14.

Threadedly fitted in the upper end of the casing 12 is a valve seat 15 against which the flat 10 upper face of the valve 14 can seat by virtue of the force of liquid directed into the cup of said element, thereby closing the atmospheric vent orifice 16 so long as liquid is flowing through the casing. The seat 15 is formed with a crown 17, spaced 15 apart from the lower portion of the seat to thus provide annular ducts 18 by means of which air may enter the casing from above the level of liquid in the tank.

It will be understood that the valve element 14 20 is proportioned with respect to the distance between the seat 15 and the tubular extension 11 so that it is entirely free to move vertically a distance limited only by said extension and said seat and that it is thereby adapted to freely rest upon 25 the extension when the flow of water through the casing ceases. Thus, the cup in the underside of element 14 directly confronts or faces the orifice 13. It will be further noted, particularly on reference to Figures 5 and 6 that the element 30 14 is provided with substantially hexagonal ends 19 and 20 and an intermediate reduced cylindrical body portion 21, the diameter of the latter being less than that of the diameter of the bore of the casing 12. This provides sharp edges at the intersection of the flat faces of the ends 19 and 20 35 adapted to have scraping contact with the walls of the bore of the casing such as will hold same in a smooth clean state and free from foreign matter and incrustation or scale.

40 The operation of the invention is as follows:

In Figure 3 of the drawing, let it be assumed 45 that water is flowing under ordinary city pressure through the ball cock and into the casing 12 of the filling tube. The valve element 14 which normally rests upon the tubular extension 11 and has its cavity or cup disposed directly over 50 the orifice 13, will be raised by the pressure of the water to thereby take the position shown in said figure, during which time the vent orifice 16 is closed to prevent air from entering the casing 12. By reason of the fact that no air is permitted to 55 enter the system during the tank filling operation, it follows that the water is silently delivered to the tank. As soon, however, as the plug P1 falls to its closed position following full raised position of the float rod R, the valve element 14 falls by gravity to the position shown in Figure 1. In so doing, the atmospheric vent orifice 16 is uncovered

and air will enter the valve casing 12 and thereby break a vacuum induced in pipe P. In Figure 1, W indicates the approximate level of water in the tank when the rod 14 is fully raised, and it thus follows that the casing 12 is devoid of water when said tank is filled. It is for this reason that suction induced in the ball cock or pipe P will be promptly broken, such as will prevent water in the tank from returning to the pipe P by siphonic action. 10

While we have shown a specific form of valve element 14, the function of which is to open and close communication between the tank T above the normal level of water therein and the pipe P, it is to be clearly understood that we are primarily 15 concerned with the provision of any equivalent of said valve which will function timely with the familiar operations of the ball of the rod 14.

What is claimed is:

1. A device of the class described comprising a 20 valve casing having a chamber provided with an upper atmospheric vent and a lower outlet adapted for connection to a filling tube; the casing having a tubular inlet portion adapted for connection to the outlet of a ball cock and extending across said chamber with an upwardly 25 opening port in such portion through which water from the ball cock can discharge upwardly into the chamber; and a valve element working in the chamber between the atmospheric vent and said 30 tubular portion to rest upon the latter and open said vent so as to place the chamber in communication with atmosphere when no water is flowing from the ball cock, and to be elevated to close said vent by water from the ball cock discharging 35 into the chamber through said port.

2. A device of the class described comprising a 40 valve casing having a chamber provided with an upper atmospheric vent and a lower outlet adapted for connection to a filling tube; the casing having a tubular inlet portion adapted for connection to the outlet of a ball cock and extending across said chamber with an upwardly opening port in such 45 portion through which water from the ball cock can discharge upwardly into the chamber; and an inverted cup-shaped valve element working in the chamber directly above the port of said tubular portion to normally rest upon the latter under the action of gravity and open said port so as to place the outlet of the ball cock in communication 50 with the atmosphere through said vent, chamber, interior of valve element, and ported tubular extension, and to be elevated to close said vent by water from the ball cock discharging into the 55 chamber through said port.
